(57) **CLAIM**

The ornamental design for a portable power station, as shown and described.

DESCRIPTION

FIG. 1 is a front and top perspective view of a portable power station showing my new design.

FIG. 2 is a rear and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a front and top perspective view when 4 sections of a portable power station are in separate status.

FIG. 10 is an enlarged view of a portion indicated with "10" in FIG. 1; and,

FIG. 11 is an enlarged view of a portion indicated with "11" in FIG. 2.

The broken lines in the figures illustrate portions of the portable power station that form no part of the claimed design.
